UNITED STATES PATENT OFFICE

SAMUEL WEISS, OF BROOKLYN, NEW YORK

MACHINE FOR MAKING MARKING TAGS

Application filed June 29, 1932. Serial No. 619,859.

My invention relates to improvements in a machine for making marking tags and it consists in the novel features, which are hereinafter more fully described.

5 One of the objects of my invention is to produce a perfected automatic machine for making marking tags from strips of metal and cloth.

10 Another object of my invention is to have the said machine operated in conjunction with a punching press, which may be of standard or special design.

15 Another object of my invention is to have the production of the marking tags by the said machine proceed at a rapid rate.

20 A still other object of my invention is to have the metal and cloth, which are employed for making said tags, automatically fed to the machine and the waste metal automatically removed from the machine.

25 Another object of my invention is to have the different steps of making the said tags by the said machine proceed simultaneously, thereby saving time and labor.

30 A further object of my invention is to prevent breaking or distortion of parts of the machine during the operation.

35 A still other object of my invention is to have the production of the said marking tags by the said machine proceed with a minimum of noise.

Another object of my invention is to have the said machine compact, strong, simple, durable and inexpensive.

35 Other objects and advantages will hereinafter appear.

I attain these objects by the machine for making marking tags, one form of which is illustrated in the accompanying drawings or by any mechanical equivalent or obvious modification of the same.

40 In the drawings Fig. 1 is a front elevation of the machine, omitting some parts for the sake of clearness.

Fig. 2 is a front elevation of a detail which is hereinafter described.

45 Fig. 3 is a side elevation of the same detail looking from left to right in Fig. 2.

50 Fig. 4 is a fragmentary view of another

detail partly in elevation and partly in section on the line 4—4 of Fig. 5.

Fig. 5 is a part sectional plan view of my improved machine for making marking tags on the line 5—5 of Fig. 1 showing an outline of the forming dies, which are hereinafter described, omitting the characteristic openings in the dies for the sake of clearness, and showing sundry parts of the machine, which are connected thereto and associated therewith.

Fig. 6 is a plan view in full size of one of the multiple forming dies, which are herein-after described, showing the characteristic openings therein, which correspond to outline of the staples.

Similar characters refer to similar parts throughout the several views.

Fig. 7 is a side view of the detail shown in Fig. 4 looking from left to right in Fig. 4 and showing some parts in elevation and one part in cross section.

11 designates the main frame of a punching press and 12 the crank shaft which is re-volvably mounted thereon.

75 A flywheel 13 is shown as secured to said shaft 12 and is kept from being displaced lengthwise of said shaft by means of a collar 14 on the latter.

80 A pitman 15 is swivelled at one end thereof on the crank pin 16 of said shaft 12 and is shown as connected at the other end thereof to a ram 17 by means of a ball 18 and plate 19.

85 A screw 20 adjustably connects said ball 18 to said pitman 15, and an apertured collar 21 is secured to said screw 20 and serves to receive in its apertures the end of a short lever or pin whereby to turn said screw 20 to adjust the position of the ram 17 with re-90

lation to said pitman 15.

95 A bevel gear 22, which is shown by its pitch cone in Fig. 1, on said shaft 12 serves to transmit power and motion to the mechanisms and other parts of the machine by means of sundry gears and spindles, which are hereinafter described.

100 All the bevel gears and mitre gears are shown by their pitch cones in the drawings in this application.

The frame 11 is shown as terminating at the lower end thereof in a base 23, and a pressplate 24 is positioned thereon. Bearing members 25 are shown as positioned on said press plate, and a bolster plate 26 is disposed above said bearing members 25.

A turntable 27-28 is placed in a corresponding recess in the bolster plate 26 and consists of a die carrier 27 and an extension 28 thereunder, which has secured thereto at the underside thereof four crown pins 29; the latter are intermittently propelled by a cam 30 which is formed integral with a sector of a disc 31 and a hub 32 on a shaft 33, which is hereinafter described. Said cam 30 is shaped like a sector of a helical member or thread, and extends over substantially one quarter of a revolution on the peripheral part of said hub 32.

The disc 31 extends over substantially three quarters of a revolution on the peripheral part of said hub 32 and is disposed transversely to said hub 32 and shaft 33 and is positioned in a plane which is also perpendicular to the plane of said turntable 27-28, and passes through a diameter of the latter. The disc 31 is mounted to revolve intermediate said two pairs of pins 29 in a direction as shown by the arrow in Fig. 7, thereby keeping said pins 29 with said turntable 27-28 stationary during three quarters of a revolution; during the remaining one quarter of a revolution said cam 30 moves one of said pins 29 which it intercepts from the left side of said disc 31 in Fig. 4 to the right side thereof, thereby rotating the turntable 27-28 through a quarter of a revolution in a direction as indicated by the arrow in Fig. 5.

Four multiple forming dies 34 are placed each in a corresponding recess in said die carrier 27 in positions as shown in Fig. 5 with the center lines of the dies at a distance of a quarter of a revolution from each other; gauge plates or nest plates 35 are placed over said dies 34 and secured therewith to said carrier 27.

A multiple blanking die 36 is secured at one end thereof to said bolster plate 26, and with the other end thereof extending over one of said forming dies 34 and gauge plate 35 at the rear of said carrier 27, to receive thereon the repeated blows or strokes of a set of punches 37, which are shown as carried by a punch holder or plate 38, which is secured to the underside of said ram 17.

Two of the punches 37 are shown in Fig. 1 of the drawings and two more are omitted for the sake of clearness; the blanking die 36 is provided with four individual openings for the staples of mark tags, as shown in Fig. 6.

A strip of metal 39 is passed over the blanking die 36 between two guides 40 and is intermittently fed in a direction from right to left in Fig. 1, to have staples 10 for marking

tags punched therefrom. The mechanism for feeding said strips 39 is hereinafter described.

Guides 40 are secured to said die 36 and are placed one rearwardly of said strip 39 and one forwardly of said strip 39.

The staples 10 which are severed from the strip 39 are deposited in the corresponding nests or gauges 35; all of said nests 35 are provided with suitable openings for the staples 10, which nest on the top of the corresponding forming dies 34; each of said dies 34 is provided with openings to receive therein the finished staples 10 after they are bent into the shape of a stirrup by means of a set of punches 41. The latter are carried by the horizontal plate 43 on a bracket 42 which is shown as positioned at and is secured to the right side of the ram 17.

This action of bending the staples is performed by said punches 41 and each of said dies 34 when the latter is positioned at the right side of the carrier 27, after the carrier has been revolved through a quarter of a revolution from the position at which said staples 10 have been blanked flat by said punches 37 and die 36.

Strips of cloth or tape 44 are passed over the front part of said carrier 27 and the corresponding die 34 which is positioned thereon after the finished staples 10 have been left deposited in said die at the completion of the bending operation and after said turntable has been rotated through a second quarter of a revolution from its above position of blanking; the strips 44 are intermittently fed from right to left in Fig. 1 by a mechanism which is hereinafter described.

In this last position the finished staples 10 are fastened to the tapes 44 by means of a set of upwardly striking punches 45 which are carried by a block 46, which is connected to the forked forward end of a substantially horizontally disposed lever 47 by means of a short vertical link 48. Said lever 47 is pivotally connected by means of a spindle 49 to the frame 11 near the base 23 of the press.

The rear end of said lever 47 is provided with a follower 71, which is actuated by a suitable cam 72 on a shaft 73, which receives its motion from the gear 22 through a gear 74 which is in mesh with said gear 22, a pair of bevel gears 75 and 76 and an inclined spindle 77, which extends downwardly rearwardly from said gear 74 to said gear 75.

The two ends of said spindles 77 are shown in Figs. 1 and 5; but the greater part of the length of said spindle 77 between said gears 74 and 75 are omitted in the drawings. The brackets supporting said spindle 77 in position are also omitted for the sake of clearness.

The punches 45 push the bent staples into the strips 44 during the upward stroke of the punches 45, and the strips 44 are being held down during this fastening operation by

means of a set of resiliently mounted punches 50, which are carried by a compound block 51-52 which is resiliently slidably and adjustably connected to a bracket 53; the latter is shown in Fig. 1 as secured to the front of the ram 17; the block 51-52 with the punches 50 have been omitted from Fig. 1 for the sake of clearness and are shown in Figs. 2 and 3 respectively in front elevation and side elevation looking from left to right in Fig. 1.

Multiple guides 54 are provided for said tapes 44 under said punches 50, which terminate at the lower ends thereof in cup shaped dies to cooperate with the upper ends of the punches 45 to turn down the transverse claws 55 of the said staples 10 on to the top of said tapes 44, thereby securing said staples to said tapes 44.

20 After the third quarter of a revolution of said carrier 27, each of said dies 34 remains idle for the duration of one revolution of the main shaft 12 of the punching press. After the fourth quarter of a revolution of the carrier 27 each of said dies 34 returns to its original position under the blanking die 36.

The operation of cutting off of the completed tags is performed by part of the same mechanism which feeds the said strips 44, as 30 will be hereinafter described.

The disc 31 keeps the turntable 27-28 with the dies thereon substantially in registration with the sundry punches which cooperate therewith. To make the registration more perfect a register-pin 56, which is preferably tapered at the lower end thereof, is provided, to be carried by a bracket 59 on the ram 17 and a corresponding opening 57 is provided through the bolster plate 26 and a similar opening 58 is provided through each of the dies 34 to receive the pin 56 therein during each downward stroke of the ram 17.

The pin 56 is slidably resiliently connected to the double flanged bracket 59, which is shown in Fig. 1 as secured to the left side of the ram 17. A nut 60 is connected to said pin 56 above the lower flange of said bracket 59 and serves as an abutment for the lower end of a spring 61, which abuts at its upper end against the underside of the upper flange of said bracket 59. The pin 56 has secured thereto at the upper end thereof a rider 62, which is shown as tapered at the lower end thereof and is normally disposed opposite the reversely inclined end of a lever 63, which is pivotally connected at one end thereof to the inner end of an upwardly extending branch 64 on said upper flange of the bracket 59; the other end of the lever 63 is connected by means of a tensile spring to the outer end of said branch 64, and has secured thereto at the underside thereof an electrically insulated contact 65, which is placed in juxtaposition to another electrically insulated contact 66, which is secured to the outer end of a

downwardly extending branch 67 on said upper flange.

Electric conduits 68, 69 connect the contacts 65 and 66 respectively to a source of electrical energy, such as a battery 70 or a lamp socket, and form therewith a normally open circuit.

Failure of the punches of the machine to register with the dies thereof will cause the lower end of the pin 56 to be intercepted by the carrier 27, thereby raising the pin 56 with the nut 60 thereon with relation to the bracket 59 against the resistance of the spring 61 on said nut 60 and thereby also raising said rider 62, which reacts on the inner end of the lever 63, thereby turning the same in a counter clockwise direction.

This rotation moves the outer end of the lever downwardly, thereby distending the tensile spring connected thereto and causes the contacts 65 and 66 to close the circuit.

A suitable solenoid or other electrodynamic member may be placed in the said circuit and the action thereof may be arranged automatically to disconnect a clutch 71 on the punching press, thereby discontinuing the operation of the machine until it is inspected and the cause of the disturbance removed.

The mechanism for feeding the metal strip 39 includes a pair of feed rolls 78 and 79, which are rotatably mounted by means of spindles 80 and 81 respectively to the upper and lower sections 82 and 83 of a two part frame, which sections are pivotally connected to each other at one end thereof by means of a spindle 84 and are pressed towards each other by means of a spring 85 encompassing a vertical stud bolt 86 which is secured to the lower section 83; the spring 85 abuts at the lower end thereof against the top of the upper section 82 and at the upper end thereof against a washer 87 under a nut 88 on said bolt 86.

The strip 39 is taken from a suitably positioned roll of sheet metal which is not shown in the drawings and passed between said spring pressed feed rolls 78 and 79. A ratchet disc 89 is secured to the spindle 81 at the rear end thereof and is intermittently rotated by means of a spring connected pawl 90, which is pivotally connected by means of a pin 91 to an oscillating plate 92, which is pivotally connected by means of a pin 93 to a connecting rod 94 which is made integral with the strap 95 on an eccentric 96.

The eccentric 96 is secured to a shaft 97, which is revolvably mounted in bearings 98 on one of said bearing members 25 at the right side of the machine and extends rearwardly from and transversely to the front of the machine as shown in Fig. 1.

The shaft 97 is driven by the shaft 73 by means of a pair of mitre gears 99 and 100, which are shown in Fig. 5 and are secured to

the ends of the shafts 97 and 73 respectively.

The shaft 73 is revolvably mounted in bearings 101 and 102 which are carried by brackets 103 and 104 respectively, which are secured to the frame 11 of the machine at the rear end thereof.

The shaft 33, which carries the disc 31 and cam 30 for actuating and controlling the motion of the turntable 27-28, is revolvably mounted in said bearing plates 25 and is driven by a rearwardly extending shaft 105 by means of a pair of mitre gears 106 and 107, which are secured respectively to said shaft 33 and said shaft 105, which is in turn driven by said shaft 73 by means of a pair of mitre gears 108 and 109 which are secured respectively to the shafts 73 and 105. The shaft 105 is revolvably mounted in a pair of bearings 110 on said plate 25 at the left side of the machine.

The mechanism for feeding the strips of cloth or tapes 44 includes a slotted crank 111 which is secured to the forward end of the shaft 97 and has adjustably pivotally connected thereto by means of a pin 112 one end of a connecting rod 113, the other end of which is pivotally connected by means of a pin 114 to the lower end of a lever 115; the latter is pivotally connected at an intermediate point thereof by means of a pin 116 to a horizontal sliding block 117 and at the upper end thereof by means of a spindle 118 to one end of each of a pair of parallel bars 119; the other ends of said bars 119 are pivotally connected by means of a spindle 120 to the knuckles of a pair of toggle joints 121.

The upper ends of said toggle joints 121 are pivotally connected by means of a spindle 122 to a pair of parallel walls 123, which form an extension of said block 117, and the lower ends of said toggle joints are pivotally connected by means of a spindle 124 to a vertically reciprocating block 125, which is vertically slidably positioned between said walls 123.

The walls 123 are provided with vertical slots, for permitting the ends of said spindle 124 to reciprocate therein vertically; the walls 123 also have therein a horizontal slot for permitting the ends of the spindle 120 to reciprocate therein substantially horizontally.

The walls 123 have secured therebetween a horizontally disposed lower blade *a*, and said block 125 has secured thereto at the underside thereof a vertically disposed blade *b* in shearing relation to said blade *a*.

The strips or tapes 44 are passed through suitable guides over the upper surface of said blade *a*, to be severed by said blade *b* when said block 125 is moved downwardly by said toggle joints 121 near the dead center position of said lever 115 when the rod 113 begins its stroke from right to left in Fig. 1, as the rod is actuated by said crank 111. On the re-

turn stroke of said rod 113 moving from left to right in Fig. 1 the toggle joints 121 begin to raise the block 125.

A stop *c* is provided on the block 117 to intercept the lever 115 and discontinue the motion of said toggle joints 121 and said block 125 after said blade *b* has been raised above the level of the tapes 44.

Rotation of the crank 111 and the motion of the parts connected thereto then moves said block 117 on the bolster plate 26 a desired distance with the blade *a* below the strips 44 and with the blade *b* above said strips, until the motion of the rod 113 and lever 115 is reversed; the strips 44 are then gripped between said blade *a* and a pair of pins *d* which are positioned at the underside of said block 125 and have their upper ends secured to the underside of said block 125.

The continued rotation of the crank 111 thereupon causes the said block 117 to draw the strips 44 from right to left in Fig. 1 by means of said pins *d*, which are carried by said block 125 until the motion of the lever 115 is again reversed.

By varying the position of the pin 112 in the slot of the crank 111 different length of marking tags may be produced. To guide the motion of said block 117 on said plate 26 a horizontal guide rod 126 is provided, which is shown in Fig. 5 of the drawings; the rod 126 is supported by a pair of vertical standards 127 which are secured to said plate 26; it is understood that said standards may be placed sufficiently far apart to allow an ample length for said guide 126.

Brackets or bolts 128 are secured at one end thereof to said block 117 at the rear thereof and terminate at the other end thereof in sockets 129, which are in sliding engagement with said guide 126.

A friction attachment is shown in Fig. 1 as connected to the front of the block 117 by means of a screw and a flange 130 on said attachment which comprises a spring chamber 131 enclosing a compression spring encompassing a pin 132; the inner end of the pin 132 is secured to a plate 133 which bears against the front of the plate 26 and the outer end of the pin 132 is slidably connected to the forward end of the said chamber 131.

Many changes may be made in the details of my machine for making marking tags without departing from the main scope of my invention, and parts of my invention may be used without other parts. I do not therefore restrict myself to the details as shown in the drawings; but I intend to include also all mechanical equivalents and obvious modifications of the same within the scope of my invention.

I claim as my invention and desire to secure by Letters Patent:

1. In a machine for making marking tags,

- the combination of a punching press, a reciprocating ram thereon, a bolster plate on said press under said ram, a turntable, rotatably mounted on said bolster plate, a blanking die secured to said bolster plate to overhang a part of said turntable, multiple forming dies on said turntable, an automatic means for intermittently feeding a strip of metal over said blanking die, an automatic 10 means for intermittently feeding strips of cloth over the turntable, a means for intermittently rotating said turntable to successively bring each of said forming dies into position under said blanking die, a means for intermittently keeping said turntable stationary, thereby successively holding said forming dies substantially in registration with said blanking die, punches on said ram disposed to act in conjunction with 15 said blanking die, whereby staples may be blanked from said strip of metal deposited into said forming dies, and other punches on said ram arranged simultaneously to act in conjunction with some of the other forming dies, positioned on said turntable out of registration with said blanking die, for forming said staples into tag attachments and upwardly acting punches operatively connected to said press for fastening the tag 20 attachment to said strips of cloth.
2. In a machine for making marking tags, the combination of a punching press, a reciprocating ram thereon, a bolster plate on said press under said ram, a turntable rotatably mounted on said bolster plate, a blanking die secured to said bolster plate to overhang a part of said turntable, an automatic means for intermittently feeding a strip of metal over said blanking die, a revolvably mounted cam, crown pins secured to said turntable at the underside thereof, to be intermittently propelled by said cam for intermittently rotating said turntable to successively bring each of said forming dies into 25 position under said blanking die, and a disc sector integral with said cam mounted to revolve therewith and disposed between said crown pins, for intermittently keeping said turntable stationary, thereby successively holding said forming dies substantially in registration with said blanking die, punches on said ram disposed to act in conjunction with said blanking die, whereby staples may be blanked from said strip of metal and deposited into said forming dies.
3. In combination with a punching press, a reciprocating ram thereon, punches carried by said ram, a turntable rotatably mounted and having a part thereof extending under said punches, dies on said turntable, a revolvably mounted cam, crown pins secured to said turntable at the underside thereof, to be intermittently propelled by said cam for intermittently rotating said turntable to successively bring each of said dies into position 30 under said punches, a disc sector integral with said cam, mounted to revolve therewith and disposed between said crown pins, for intermittently keeping said turntable stationary, thereby successively holding said dies substantially in registration with said punches.
4. In a machine for making marking tags, a punching press having thereon a ram, dies and punches actuated thereby, combined with an automatic means for insuring a more perfect registration between said dies and said punches, said means comprising a register pin, having thereon a tapered lower end, resiliently slidably mounted on said ram, said dies having therein each an opening to receive said pin, a rider on the upper end of said pin, a pivotally mounted lever disposed to be turned by the motion of said rider upwardly with relation to said ram, a means for returning said lever to its original position after said rider has been returned to its normal position and a means for disconnecting the clutch of the press by the said turning motion of said lever.
5. In a machine for making marking tags, a punching press having thereon a ram, dies and punches actuated thereby, combined with an automatic means for insuring a more perfect registration between said dies and said punches, said means comprising a register pin having thereon a tapered lower end, resiliently slidably mounted on said ram, said dies having therein each an opening to receive said pin, a tapered rider on the upper end of said pin, a pivotally mounted lever having one arm thereof in juxtaposition to said rider and disposed to be intercepted and turned thereby when the latter is moved upwardly with relation to said ram, a spring connected at one end thereof to the other arm of said lever and at the other end thereof to a part on said ram, an electrically insulated contact carried by said other arm, another electrical 40 insulated contact carried by a part on said ram opposite said first contact, each of said contacts being in electrical communication with a source of electrical energy, said contacts normally being separated, thereby keeping the circuit of said source open, said contacts being disposed to be joined by the rotation of said lever, thereby closing the circuit, an electrodynamic means, to be energized by the current in said circuit, and a means for disconnecting the clutch of said press, to be actuated by said electrodynamic means.
6. In a machine for making marking tags, a bolster plate and automatic cloth strip feeding means comprising guides for said strips on said bolster plate, a revolvably mounted crank, a connecting rod pivotally connected at one end thereof to said crank, an oscillating lever, substantially vertically disposed and pivotally connected at the low- 45

er end thereof to the other end of said connecting rod, a sliding member mounted on said bolster plate and pivotally connected to said lever at an intermediate point of the latter, thereby forming a fulcrum for the same, a side bar pivotally connected at one end thereof to the upper end of said lever a part on said member movable therewith, a substantially vertically disposed toggle joint 10 pivotally connected at the upper end thereof to the said part on said member and at the knuckles thereof to the other end of said side bar, a substantially vertically reciprocating block pivotally connected to the lower end of said toggle joint, whereby to be raised and lowered by the oscillation of said lever, substantially vertically disposed pins secured to said block at the underside thereof, a stop on said member for limiting the 20 amplitude of oscillation of said lever, a blade carried by said part at the lower end thereof with the top of said blade disposed at the underside of said strips, said blade being stationary with relation to said part, said stop being so located that the oscillation of the lever in one direction will cause said toggle joint to lift said block with the pins thereunder a limited distance to clear said tapes, whereupon the continued exertion on said 30 lever by said rod will cause said member to slide on said bolster plate a predetermined distance, whereupon the reversal of the direction of motion of said rod will cause said lever with said toggle joint thereon to depress said block with said pins thereon, thereby seizing and holding said strips therebetween and said blade, whereupon the continued exertion of the said rod on said lever will cause said member to slide on said bolster plate to its original position, thereby carrying said strips with it.

7. The elements of claim 6, combined with an automatic means for cutting said cloth strips after tag attachments have been fastened thereto, said cutting means being actuated by said crank and forming part of and operating in conjunction with said cloth strip feeding means.

8. The elements of claim 6, said block having also secured thereto at the underside thereof a substantially vertically reciprocating blade in shearing relation to said relatively stationary blade, to be brought down 55 on said strips simultaneously with said pins thereby cutting said strips into desired lengths by each descent of said block, with the blade thereon, the lower edge of said reciprocating blade not quite reaching the top 60 of the bolster plate during the carrying stroke of said member with said strips carried thereby between said pins and said relatively stationary blade, and said reciprocating blade with said block thereover being 65 raised by said toggle joint with the cutting

edge thereof above the level of said strips during the return stroke of said member.

9. The elements of claim 6, combined with an automatic means for cutting said strips after tag attachments have been fastened thereto, said crank having therein a slot for adjustably pivotally connecting the adjacent end of the connecting rod thereto, thereby adjustably varying the stroke of said member with the parts which are carried by the latter and thereby varying the lengths of the severed marking tags at the will of the operator.

10. In a machine for making marking tags, a horizontal plate for cloth strips to rest thereon and automatic cloth strips feeding means comprising a revolvably mounted shaft, a reciprocating member slidably mounted on said plate, a means for transmitting motion from said shaft to said member, a cloth strip gripping device and a toggle joint connected thereto for moving the same transversely to the strip, said device and toggle joint being carried by said member and actuated by said transmitting means, to seize said strips during the beginning of the motion of said member in one direction and to release said strips during the beginning of the motion of said member in the opposite direction, and a means on said member to limit the motion of said toggle joint, thereby limiting the motion of said gripping device in releasing said strips to the duration of a relatively short part of the motion of said member in said opposite direction.
